GRAPPLE

Donald H. Mitchell, Cranford, N. J., assignor to
Western Electric Company, Incorporated, New
York, N. Y., a corporation of New York

Application November 12, 1943, Serial No. 509,978

2 Claims. (Cl. 294—117)

This invention relates to grapples, and more particularly to grapples for transporting smooth-surfaced articles.

An object of the invention is to provide a grapple which is simple in construction, readily actuatable, and highly efficient for transporting articles.

With this and other objects in view, the invention comprises a grapple having levers pivotally connected intermediate their ends, with article gripping elements supported adjacent the lower ends thereof, the upper ends of the levers being connected, through links, to a lifting means for applying a constant gripping force to an article to be transported thereby.

Other objects and advantages will be apparent from the following detailed description when considered in conjunction with the accompanying drawing, wherein

Fig. 1 is a front elevational view of the grapple;

Fig. 2 is a side elevational view of the grapple, and

Figs. 3, 4 and 5 are fragmentary detailed views of different portions of the grapple, the first two of the connecting links and the latter of one of the gripping elements.

Referring now to the drawing, the grapple includes levers 10 and 11 which are pivotally connected intermediate their ends at 12. Each of the levers 10 and 11 is composed of two parts, or, if desired, these may be defined as pairs of companion levers, but to simplify the description they are given like reference numerals. The pivot 12 includes a suitable rod with a central spacing sleeve 14 and collars 15 disposed upon the outer ends of the rod. Article gripping elements 16 and 17 are pivotally connected at 18 and 19 to their respective levers 10 and 11. The elements 16 and 17 have pockets 20 in which are disposed gripping blocks 21, the latter being formed of a suitable material to grip and frictionally hold an article such as that indicated at 22. The lower ends of the gripping blocks 21 are tapered, as at 23, to facilitate in the movement of the gripping elements into engagement with the article. It will be noted, by viewing Figs. 2 and 5, that pairs of flanges 25 for the element 16 and pairs of flanges 26 for the element 17 are mounted to receive their respective lever portions 10 and 11. Retaining loops 28 and 29 are fixed to their elements 16 and 17 and extend around the adjacent portion of their levers 10 and 11, to maintain the elements in article receiving positions.

The outer ends of the levers 10 and 11 are respectively pivotally connected at 30 and 31 to

U-shaped links 32 and 33. The formation of the links is further illustrated in Figs. 3 and 4. In these figures tubular spacers 35 and 36 are illustrated as being mounted upon the pivots 30 and 31. The outer ends of the links 32 and 33, indicated by reference numerals 37 and 38, serve as handles for use in guiding the grapple relative to an article to be transported, or for use in removing the grapple from the article.

The inner ends of the links 32 and 33 are connected to a pivot 40, the latter being carried by a supporting element 41 provided with an aperture 42 to receive a hook 43 or other suitable connecting means of a hoist or the like for use in transporting the grapple and article. A U-shaped locating element 45, having the upper ends of its legs carried by the pivot 40, has mounted on its central portion a pad 46 which extends between the lower portions of the levers 10 and 11. Elongate apertures 47 in the legs of the element 45 receive the pivot 12 and thus hold the element against lateral displacement but for vertical movement through the aid of the collars 15.

When it is desirable to transport the article 22 or other similar articles, the grapple is moved to a position above the article, and then lowered so that the gripping elements 16 and 17 will be disposed at opposite sides of the article. While being lowered the gripping elements will be in their open positions governed by the retaining loops 28 and 29 with their contacting surfaces lying at transverse angles to readily straddle the article. The pad 46 on the element 45 serves in locating the grapple or rather the gripping elements 16 and 17 thereof relative to the article. After the gripping elements engage the upper edges of the article, they will find their positions parallel with the surfaces they engage by movement about their pivots. Furthermore, the elements may rest upon the upper edges of the article until the hoist hook is lowered sufficiently to relieve the force on the levers to allow the links 32 and 33 to open the levers and elements.

When the elements 16 and 17 have been located relative to the article, a lifting force may be applied through the aid of the hook 43 to the links 32 and 33, moving upwardly also the element 45. The elongate apertures 47 in the element 45 are of sufficient length so that at no time during the lifting of the article, will any of the weight thereof be carried by the locating element. Thus, in applying a lifting force to the links 32 and 33, the levers 10 and 11 are moved about their pivot 12, forcing the gripping elements 16 and 17 inwardly to cause the blocks

21 to firmly grip the article. The greater the weight of the article, the greater will be the gripping force applied thereto through the elements 16 and 17. The grapple may thus be transported with the article to a given position, after which it may be lowered to move the article upon a support, where further downward movement of the support 41 will release the gripping force applied to the article through the elements 16 and 17. Through the aid of the handle portions 37 and 38, the grapple may be removed from the article, after which the handle portions may be released. Here the locating element 45 serves another purpose, that of supporting the levers 10 and 11 through its connection with the supporting element 41 during the normal transportation of the grapple when not supporting an article.

Although specific improvements of the invention have been shown and described, it will be understood that they are but illustrative and that various modifications may be made therein without departing from the scope and spirit of this invention as defined by the appended claims.

What is claimed is:

1. A grapple comprising article gripping elements each having spaced pairs of flanges disposed on the outer surfaces thereof and article engaging portions on the inner surfaces thereof, pairs of spaced transversely extending levers pivotally connected to each other intermediate their ends, means to pivotally connect the lower ends of the pairs of levers, positioned singly between their respective pairs of flanges, to the flanges, U-shaped links pivotally connected to

each other at their inner ends and to their respective pairs of levers intermediate the ends of the links with the lateral connecting portions forming handles for the actuation of the link to move the levers and gripping elements into open positions, and lifting means connected to the central pivot of the links to move the links, levers and elements to move the latter into gripping engagement with an article.

- 10 2. A grapple comprising article gripping elements each having spaced pairs of flanges disposed on the outer surfaces thereof and article engaging portions on the inner surfaces thereof, pairs of spaced transversely extending levers pivotally connected to each other intermediate their ends, means to pivotally connect the lower ends of the pairs of levers, positioned singly between their respective pairs of flanges, to the flanges, U-shaped links pivotally connected to each other at their inner ends and to their respective pairs of levers intermediate the ends of the links with the lateral connecting portions forming handles for the actuation of the link to move the levers and gripping elements into open positions, lifting
- 15 20 25 30 means connected to the central pivot of the links to move the links, levers and elements to move the latter into gripping engagement with an article, and U-shaped members carried by the gripping elements and extending partially around their respective levers to be moved into engagement therewith to normally hold the elements in diagonal positions relative to each other and their levers to receive the article therebetween.
